UNITED STATES PATENT OFFICE.

WILLIAM GOLDING, OF NEW ORLEANS, LOUISIANA.

STEAM-ENGINE.

SPECIFICATION forming part of Letters Patent No. 298,081, dated May 6, 1884.

Application filed September 25, 1883. (No model.)

To all whom it may concern:

Be it known that I, WILLIAM GOLDING, of New Orleans, in the parish of Orleans and State of Louisiana, have invented certain new and useful Improvements in Steam-Engines, of which the following is a full, clear, and exact description.

My invention has reference to engines impelled by steam or other vapor, fluid, or gas capable of expansion, and in which it is proposed to cut off the impelling agent early in the stroke of the engine-piston and to work the remainder of the stroke by expansion, for the purpose of economizing the use of said agent, or, in other words, of obtaining an enlarged effect for a limited supply of it.

In expansion-steam engines, both of the single and compound kind, as ordinarily constructed and worked, for imparting rotary motion by means of a crank or cranks to a driving-shaft, there is often but little or no advantage in working the steam expansively, and where the load to be overcome is a constant one, and not of an elastic or varying description, such method of utilizing the steam, except to a very limited extent, is generally impracticable, owing to the great variation in pressure at different points of the stroke, and which produces a want of uniformity in the rotary motion of the driving-shaft that even a weighty fly-wheel, where such is practicable, only partially corrects, and that very imperfectly so. To maintain a uniform speed of the rotating engine shaft or parts, it is necessary that the power be uniformly applied to each division of the circle described, and to obtain a full economy of steam-expansion with perfect uniformity of peripheral speed and against a constant load is the leading object of my invention.

To such and other ends, including the dispensing with, if desired, a fly-wheel to assist in producing said effect, and the avoiding of all dead-center action, although these are not the special objects sought to be obtained, my invention consists in a number of independent engines grouped into separate and distinct pairs and connected with progressively set or arranged cranks on two independent shafts which are geared with and serve to rotate a main driving or combined engine-shaft, whereby the initial and diminishing pressures of the

steam or other impelling agent in the several cylinders, working expansively, are made to produce a uniform rotative effect upon the main shaft, or, in other words, the several engines are caused to maintain the initial rotative effect by the application in regular order of the initial and diminishing pressures, as hereinafter described, and pointed out in the 55 claims.

Reference is to be had to the accompanying drawings, forming part of this specification, in which similar letters of reference indicate corresponding parts in all the figures. 65

Figure 1 represents a plan of an organized system of independent reciprocating-piston cylinder-engines connected with duplicate many-cranked shafts in gear with an intermediate main or driving shaft in accordance with my invention. Fig. 2 is a side elevation of the same; Fig. 3, an end view thereof; and Fig. 4 is a diagram in illustration of the arrangement of the several cranks of the independent engines and of the geared arrangement of the crank-shafts with a main or combined engine-driving shaft. 70 75

In the arrangement shown in the drawings two parallel vertical series of reciprocating-piston cylinder-engines—that is, four in each row or series—are represented with their cylinders placed overhead; but said cylinders may be arranged below, horizontal, or in any other desired position; and the invention is not restricted to any precise number of engines that combined form but a single engine—that is, communicate rotary motion to the same driving-shaft. It will suffice here, however, by way of illustration, to refer to four engines in each row or series of engines. 90

A A indicate four engine-cylinders in one row or series, and A' A' a like number of similar cylinders in an adjacent parallel row or series. These several cylinders are all mounted on suitable frames or uprights, B, on a common bed-plate, C, and supported by upright stays or rods *b b*. The piston-rods *c c'* of these engine-cylinders may have blocks or cross-heads working in suitable guides, and are respectively connected by rods *d d'* with 95 cranks *e e' e'' e''' e'' e''' e'* on independent parallel shafts D D'. The eight separate and distinct engines to which these several cylinders A A' belong are grouped into four separate

and distinct pairs of engines having their cranks e and e' , e^2 and e^3 , e^4 and e^5 , e^6 and e^7 , set or arranged at right angles with each other, as more clearly shown in Fig. 4 of the drawings, the several cranks, in their aggregate, serving to divide the circles described by them into sixteen parts—that is, eight parts for the downstroke of their several pistons and eight parts for the upstroke thereof. The crank-shafts D D' are geared—as, for instance, by spur-gears f , f' , and g —with an intermediate or combined engine-driving shaft, E , which is relieved from all lateral pressure in its journal-boxes h by the engines on the one side of it serving to depress said shaft, while the engines on the other side exert a like tendency to raise it. Thus the shaft E floats, as it were, in its bearings. The journal-boxes i i' of the crank-shafts D D' should be so arranged and secured to their places as that on removing blocks provided for the purpose their gears f f' may be slid out of mesh with the gears g on the main shaft E . The valves of the several engines are actuated by two eccentrics, k k' l l' , for each engine on the shafts D D' thereof, according to the direction in which it is required to drive the engines, each pair of said eccentrics being connected by their rods m n and m' n' to opposite ends of slotted reversing-link o o' , up from which the vertically-guided sliding valve-rods p p' project. The reversing-links o o' of the several engines on opposite sides of the main shaft E are connected by rods q , and these rods in their turn connected by rods r with arms s on a rock-shaft, t , that is fitted with a toothed sector, u , with which a screw, w , operated by a hand wheel or crank, engages to collectively work the several valves for the purpose of starting, stopping, and reversing the several engines. Any other system of valve-gear, however, may be adopted, and the valves themselves may be of any suitable kind to work the steam expansively in the several engine-cylinders, the same either having a fixed or adjustable cut-off action, as desired. Ordinarily, however, where eight engines or engine-cylinders are used, as shown, the valves will be set to cut off the steam at one-eighth of the stroke in each direction, whereby the initial force of

the steam will be exerted on the main shaft E throughout its entire rotation and the power as derived both from the initial pressure of the steam and its expansion after being cut off will be uniformly applied to each division of the circle described by said shaft. This will give a full economy of steam-expansion with perfect uniformity of peripheral speed in cases where the load is a constant one. The several engines as thus combined and operating form but a single engine. When it is required to cut off at different points in the stroke, then the number of independent expansion-engines may be varied accordingly. Thus, when cutting off at one-fourth instead of one-eighth of the stroke, then four independent engines in place of the eight herein described will answer.

Having thus described my invention, what I claim as new, and desire to secure by Letters Patent, is—

1. In expansion-steam and other engines, the combination, with an intermediate driving-shaft, of a series of independent expansion reciprocating-piston engines, arranged in pairs on opposite sides of said shaft and geared or connected with it to rotate the same, the cranks in each pair of said engines being set at right angles with one another, and the cranks of the several engines being arranged progressively and uniformly, one in advance of the other, substantially as and for the purposes specified.

2. The combination, in the one expansion-engine, of the intermediate driving-shaft, E , the duplicate parallel crank-shafts D D' on opposite sides of said shaft, the gears f f' g , connecting the several shafts, a duplicate series in pairs, of reciprocating-piston expansion-engines having their cranks arranged, as described, progressively and uniformly, one in advance of the other, and a valve mechanism common to all the engines for simultaneously and similarly controlling them, essentially as described.

WILLIAM GOLDING.
